UNITED STATES PATENT OFFICE.

FULTON CUTTING, OF MANHASSET, NEW YORK, ASSIGNOR TO COLONIAL RADIO CORPORATION, OF LONG ISLAND CITY, NEW YORK, A CORPORATION OF DELAWARE.

DESIGN FOR A LOUD-SPEAKER HORN.

Application filed May 23, 1925. Serial No. 13,548. Term of patent 14 years.

To all whom it may concern:

Be it known that I, FULTON CUTTING, a citizen of the United States, residing at Manhasset, county of Queens, and State of New York, have invented a new, original, and ornamental Design for Loud-Speaker Horns, of which the following is a specification, reference being had to the accompanying drawings, forming part thereof.

Fig. 1 is a front elevation; Fig. 2 is a side elevation of my ornamental design for loud speaker horns.

I claim:—

The ornamental design for a loud speaker horn, as shown.

FULTON CUTTING.
